[57] CLAIM

The ornamental design for a ground insertable drink holder, as shown and described.

DESCRIPTION

FIG. 1 is a top plan view of a ground insertable drink holder showing my new design;

FIG. 2 is a side elevation view thereof, the remaining sides being identical and the broken line showing of the additional holders being for illustrative purposes only and forming no part of the claimed design;

FIG. 3 is a bottom plan view thereof; and,

FIG. 4 is a side elevation view thereof.
